AUTOMOBILE DOOR HANDLE

Clayton E. Anderson, Highland Park, Mich., assignor to
General Motors Corporation, Detroit, Mich., a corpora-
tion of Delaware

Application September 23, 1953, Serial No. 26,917

Term of patent 7 years

(Cl. D10—8)

To all whom it may concern:

Be it known that I, Clayton E. Anderson, a citizen of the United States and a resident of Highland Park, Wayne County, Michigan, have invented a new, original, and ornamental Design for an Automobile Door Handle, of which the following is a specification, reference being had to the accompanying drawing, forming a part hereof.

Fig. 1 is a front elevational view of an automobile door handle, showing my new design;

Fig. 2 is a perspective view thereof;

Fig. 3 is an end elevational view;

Fig. 4 is a sectional view taken on the plane indicated by the line 4—4 in Fig. 1;

Fig. 5 is a sectional view taken on the plane indicated by the line 5—5 in Fig. 1; and

Fig. 6 is a sectional view taken on the plane indicated by the line 6—6 in Fig. 1.

I claim:

The ornamental design for an automobile door handle, substantially as shown.
